NELSON M. BAKER
INVENTOR

BY Harry H. Styll
ATTORNEY

UNITED STATES PATENT OFFICE

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

RECEPTACLE

Application filed October 26, 1929. Serial No. 402,649.

This invention relates to improvements in receptacles and has particular reference to an improved means of identifying said receptacles and to the process of attaching 5 said identifying means.

The principal object of this invention is to provide a novel and simple means whereby the user of a receptacle such as a spectacle or eyeglass case may have a personal 10 identifying mark placed thereon.

Another object of this invention is to provide means whereby such a mark may be placed on the case without the use of special equipment or tools.

15 Another object of this invention is to allow cases to be supplied by the manufacturer to the small dealer ready for the application of the marking device without said cases being unsalable should no mark be applied thereto by the dealer.

Another object of the invention is to confine the marking device to as few parts as possible in order to reduce the cost of manufacture and to obtain simplicity of assembly.

Other objects and advantages will become apparent from the following description taken in connection with the accompanying drawings and it will be understood that 30 many changes may be made in the details of construction, arrangement of parts and steps in the process without departing from the spirit of the invention as expressed in the accompanying claims. I, therefore, do 35 not wish to be limited to the exact details shown and described as the preferred forms only have been shown by way of illustration.

In the drawings:

40 Fig. I is a perspective view showing the improved form of case.

Fig. II is an inside view of the improved case showing a feature of the construction.

45 Fig. III is an enlarged, fragmentary sectional view of the case cover showing another feature of the invention.

Fig. IV is a top or plan view of the fragmentary portion shown in Fig. III.

50 Fig. V is a front view of the marking device.

Fig. VI is a view of the underside of the marking device.

Spectacle and eyeglass cases have heretofore been of merely utilitarian value as receptacles in which the fragile lenses were 55 protected. Prescription dealers usually provided customers with such cases gratis, these often bearing some advertising matter to compensate for the slight cost to the dealer. It will be seen therefore that the 60 attitude of the dealer and users has recently changed when considerable sums are paid for so-called "modernistic" cases and expensive leathers are used in their manufacture. These present-day cases are objects of some 65 intrinsic worth far removed from the crude receptacles of the past and it is evident that, as in other similar personal possessions, a means of ready identification is necessary 70 whether the case is empty or contains the owner's spectacles or eyeglasses.

It is the prime object of my invention therefore, to provide an identifying means, such as a monogram button, which will be easy for the small dealer to attach to the 75 case if the customer should so desire, the case being specially prepared at the manufacturers for the reception of such a mark, but being at the same time quite undisfigured and salable should no mark or addition be applied thereto by the dealer.

In the accomplishment of the invention I have shown in the drawings, wherein similar characters of reference denote corresponding parts, a spectacle or eyeglass case 1 85 which is preferably made with a lid 2 and body 3 of metal or other suitably sturdy material. The lid 2 is of the usual spring type and closes upon a lip 4 which retains the spectacles or eyeglasses in the case without slipping. Having formed the usual 90 type of case I now depart therefrom by piercing a number, preferably four, of small slots 5 in the lid 2 as shown in Figs. III and IV. The position of the slots 5 is governed by the desired location of the marking device 6 which may be placed at the lower 95 left-hand corner as shown in Fig. I or other suitable position. The shape of the slots 5 is also governed by the shape of the device 100

6 and may be rectangular as will be apparent from the following description of the construction thereof.

In constructing the marking device or button 6 I first form by blanking or other suitable method the dish-shaped top portion 7 of metal or other suitable material which may be circular or of other preferred shape. I next attach to the underside 8 thereof a strip of similar material having a depending prong 9 at each end as shown in Figs. V and VI. For the complete device I form two of these buttons 6 one of which, to be placed on the exterior of the case, I suitably mark with a monogram, emblem or other device. This mark may be printed on the surface of the button after treatment with a celluloid coating or other suitable substance to give a smooth, glossy and non-tarnishable finish similar to the well-known coat badges and other celluloid coated articles.

The button 6 to be placed on the interior of the lid 2 need not be so finished with celluloid but is placed directly on to the said lid 2 and the prongs 9 bent over on the exterior side to retain it in position. I then proceed to line the case 1 with a suitable lining 10 of velvet or other soft material and so cover the inner button 6 completely and hide it from view as shown in Fig. III.

I next cover the exterior of the case 1 with a suitable finishing material 11 such as grained leather or leather-like material suitably embossed or color-printed. The bent prongs 9 on the exterior of the lid 2 are therefore hidden from view as are two of the holes 5 of the four previously pierced.

The case is now in condition to be sold if desired without further attention as no signs of the hidden button are visible. Cases in this state may be supplied in quantity to the prescription dealers together with quantities of the coated buttons 6 suitably monogrammed. The dealer has merely to select the desired button 6 and with a needle or other suitable probing means find the hidden holes 5 after which the prongs 9 may be inserted and pressure applied to bend them under the interior of the lid 2. It will be obvious that when the prongs 9 strike the underside 8 of the button 6 already in position they will be directed towards the center by the dish shaped surface and so clamp the top portion 7 on to the exterior of the lid 2. Pressure for this purpose may be applied with the fingers or with the ordinary flat faced pliers found in any prescription dealers establishment.

It will be apparent that I have provided extremely simple means of adding to the appearance, safety and identification means of a spectacle or eyeglass case in such a way that whether the device is used in its entirety or only one portion the case so fitted

is quite usable. It will also be apparent that the cost of manufacture of the identification means is almost negligible and the labor of fitting reduced to a minimum.

Having described my invention, I claim:

1. A receptacle having a base portion, an interior lining therein and an external covering thereover and having two sets of separated openings arranged at an angle to each other through the base portion, a button member on the inside of the base portion having prongs extending through one set of the openings and clamped down over the outside of the base portion, the lining extending over the button on the inside of the receptacle and the covering extending over the clamped prongs and over the other set of openings on the outside of the receptacle.

2. A receptacle having a base portion, an interior lining therein and an external covering thereover and having two sets of separated openings arranged at an angle to each other through the base portion, a button member on the inside of the base portion having prongs extending through one set of the openings and clamped down over the outside of the base portion, the lining extending over the button on the inside of the receptacle and the covering extending over the clamped prongs and over the other set of openings on the outside of the receptacle, and a button on the outside of the covering having prongs extending through the covering and through the second set of openings and clamped over the base portion on the inside of the receptacle.

NELSON M. BAKER.
